TELAUTOGRAPH APPARATUS.

Application filed September 29, 1928. Serial No. 309,272.

The present invention relates to improvements in telautograph apparatus and particularly to improvements in receivers arranged to operate with variable strength 5 direct current transmitters.

In such telautograph apparatus the bucket coils which serve to operate the receiver pen are energized by currents sent out from the transmitter over the writing lines, these 10 bucket coils being located in the field produced by field magnets. The coils of the field magnets are energized by what may be termed a power circuit, because it carries a relatively heavy current as compared 15 with the small currents of the writing lines. The power circuit may be energized by a single source of electricity, which may supply the entire telautograph system, or by local sources at each station. In order that 20 the power circuit may be closed at the receiver from the transmitter as soon as transmission begins and be opened as soon as transmission ends, it is common to provide a relay in one of the writing lines, this 25 relay closing the power circuit containing the receiver field magnets so long as writing current is flowing over the said writing line.

The paper shifter for the receiver has heretofore been included in the power circuit so that the magnets of said shifter are energized to make one feed of the paper when the said writing line relay closes the said power circuit at the receiver, this paper shifter making a return stroke under the 30 influence of gravity, ready for another paper feeding action, when the said writing line relay is deenergized.

When the field magnets and the magnets of the paper shifter are energized from the 35 power circuit and the closure of the power circuit is accomplished by a relay in the writing line certain difficulties are encountered due to the discharge of the field magnet coils through the paper shifter magnets 40 when the power circuit is opened at the contacts of said relay, the discharge current from the field magnets tending to cause an undesired paper feeding operation of the paper shifter. To avoid this it has been 45 common to arrange the paper shifter coils

in multiple with the field magnet coils, and provide the line relay with two sets of contacts, one set for short-circuiting a part of the field magnet winding when the relay is deenergized, and the other set for closing 55 simultaneously the power circuit containing the field magnet coils and the paper shifter coils, the arrangement of the two sets of contacts being such that the line relay will close the short circuit for the field magnet 60 coils before opening the power circuit and vice versa. This requires a delicate adjustment of the contact devices and often leads to a resulting lack of reliability in operation requiring frequent inspection and considerable care in maintaining the proper 65 adjustment of the contact points.

To avoid this disadvantage, the system at the receiver is sometimes modified so that the line relay is used to close only the branch 70 of the power circuit containing the paper shifter, and then the latter closes the branch containing the field magnet coils, for which purpose the paper shifter is provided with circuit making and breaking devices. In 75 this construction the paper shifter also closes the pen lifter line at the receiver. As the paper shifter must make a relatively long stroke to feed the paper it becomes necessary to provide special circuit making and 80 breaking mechanism which allows a long movement to the operating mechanism with a short movement of the contact springs. Such an arrangement may lead to an undesirable braking action on the paper shifter, so that in case of any alteration of the 85 adjustments of the apparatus, the stroke of the paper shifter is interfered with, with the result that the paper feed is not uniform.

It is the object of the present invention 90 to provide a system and apparatus for the receiver circuits whereby the above disadvantages will be avoided. With this general object in view and some others which will be obvious to those skilled in the art from 95 the description hereinafter given, the invention comprises a receiver system and apparatus in which the line relay is provided with one set of contacts only, these contacts controlling a branch of the power circuit 100

in which are included in multiple the coils of the paper shifter and the coils of a field control relay, this relay controlling another branch of the power circuit containing the 5 field magnet coils. This relay also controls two branches of the pen lifting line, closing one and opening the other and vice versa, one of these branches including the coils of the pen lifting magnet and the other 10 branch including the coils of a signalling buzzer, the latter branch being closed when the field control relay is in its deenergized condition. Furthermore, the complete system embodying the invention in its best 15 form comprises means for protecting the field control relay contacts against the oscillatory discharge from the field magnet coils due to opening the circuit, and also comprises a high resistance winding on the field 20 magnet in multiple with the usual energizing coils of said field magnet, this high resistance winding being so wound that the oscillatory discharge through it will neutralize the magnetizing effect of the discharge 25 through the usual energizing coils.

The means for protecting the field control relay contacts against the oscillatory discharge of the field magnet coils is most advantageously a shunt branch of the power 30 circuit shunted around the said contacts and provided with a condenser to pass the oscillatory discharge, while blocking any direct current.

The invention also comprises a relay 35 construction particularly important in connection with the receiver system hereinbefore pointed out.

The preferred embodiment of the invention is illustrated in the accompanying 40 drawings, in which

Fig. 1 is a diagrammatic view of so much of a telautograph receiver system as is necessary to explain the invention,

Fig. 2 is a front elevation of a field control relay embodying features forming part 45 of the invention,

Fig. 3 is an end elevation and

Fig. 4 a top view of the said relay;

Fig. 5 is a front elevation of a writing line 50 relay embodying features forming part of the invention, and

Fig. 6 is a side elevation of the said line relay.

Referring to the drawings, and particularly to Figs. 2 to 4, the field control relay comprises a U-shaped frame, 4, of magnetic material one leg, 5, of the frame extending beyond the other. To the long leg, 5, a plate spring, 7, of steel is clamped by a clamping 55 bar, 8, held by two screws, 9, passing through the clamping bar and through the plate spring, 7, into the end of the leg, 5.

To the inner side of the plate spring an armature, 10, is secured in such a way as to 60 allow a certain freedom of movement of the

plate spring relative to the armature and vice versa. This is accomplished by providing a short spacer block, 11, between the plate spring and the armature and securing the armature, the spacer block and the plate 70 spring together in any suitable manner as, for example, by rivets passing through all the parts. In order to maintain a good magnetic circuit the armature is made long enough so that one end of it extends over the 75 face of the short leg, 6, of the U-shaped frame, while the other end of said armature reaches close to the side of the long leg, 5, of the U-shaped frame, so that the air gaps will be reduced as much as possible, the plate 80 spring itself assisting somewhat in reducing the reluctance of the magnetic circuit.

The plate spring, 7, has its free end extended beyond the U-shaped frame, so as to project over a pair of contact posts, 12, and 85 13, each of which is provided with a contact point as indicated at 14 and 15. The said free end of the plate spring is slotted longitudinally so as to form two flexible tongues, 7^a and 7^b, each of which is provided on its 90 under or inner face with a contact point, these points, 16, and 17, coacting respectively with the coacting contact points 14 and 15 carried by the contact posts, thus constituting two sets of front contact devices for 95 a purpose hereinafter more fully explained. The plate spring, 7, also carries a back contact point, 18, which coacts with a contact point, 19, carried by the overhanging end, 20, of a back contact post, 21. The front contact posts, 12 and 13, and the back contact post, 21, are constructed and mounted upon the U-frame as follows: Upon the short leg, 6, of the U-frame there is placed a plate member, 22, having an inturned flange, 22^a. 100 The front contact posts 12 and 13 are mounted outside the plate member, 22, and they together with the said plate member are held securely to the short leg of the U-frame by screws, indicated at 23, passing 105 through longitudinal slots in the front contact posts, thence through holes in the plate member, 22, and into threaded holes in the U-frame, suitable bushing washers, 24, of insulating material being provided between the 110 plate member, 22, and the respective contact posts, 12 and 13, so as to insulate the latter.

For the same purpose, the screws, 23, are provided with insulated bushing washers 25, the bushings of which enter the slots in the 115 contact posts. Outside the bushing washer each screw is provided with a metal washer 26, and, outside this, with a spring locking washer 27, beneath the head of the screw. By loosening the two screws of a contact post, the said post may be adjusted longitudinally as desired and by then tightening the screws it may be clamped firmly in the 120 adjusted position. For convenience in connecting each contact post to a circuit con- 125

ductor one end of each post is sloped outward and provided with a terminal screw and washer, 28, as indicated in the drawings.

The back contact post, 21, is secured to the 5 inturned flange 22^a of the plate member by screws 29, suitable bushing washers 30 of insulating material, located on the screws between the contact post and the said flange, serving to insulate the back contact post from 10 the inturned flange, 22^a. The screws also are provided with bushing washers 31, metallic washers 32, and spring locking washers 33. In the present construction the back contact post is provided at one end with a 15 terminal screw and washer, as indicated at 34 and 35, in the drawings.

To the U-frame there is secured the usual magnet core, 36, on which is fixed a magnet winding Fer. It will be observed that the 20 relay hereinabove described has a divided magnetic circuit. That is, if it is assumed that the direction of the magnetic flux through the core is from the free end of the core toward its junction with the U-frame, 25 the flux divides at said junction, part flowing back along one leg of the frame, and part along the other leg of the frame. The plate spring 7, is made with such a set that normally it slopes away from the end of the 30 core and the short leg 6, of the U-frame, whereby the air gap between the armature 10 and the end of said short leg 6 is greater than between the armature and the end of the core 36. Hence the reluctance of that 35 branch of the magnetic circuit which includes the long leg 5 of the U-frame is less than the other branch of the magnetic circuit. As a result more of the magnetic flux will flow over said long leg 5 than through the short 40 leg 6 at the instant when the magnet is initially energized, the parts being so dimensioned that the pull of the core 36 at this time will serve to draw the armature toward the core against the resiliency of that part 45 of the plate spring between the point of attachment of the armature and the clamped end of the plate spring. As the armature approaches the core, the air gap between the end face of the short leg and the armature 50 reduces, thereby decreasing the reluctance of that branch of the magnetic circuit. Simultaneously the air gap between the core and the armature reduces. As a result of these reductions in reluctance, the flux is 55 materially increased and therefore there is a relatively strong pull on the armature toward the latter end of its movement. The air gap between the end face of the short leg and the armature is greater angularly 60 than the gap between the front contacts so that, at the moment these contacts close, the armature can still travel further toward the core and short leg. Owing to the increasing pull on the armature it continues to move 65 toward the short leg after the front contacts have closed, this resulting in bringing into action the resiliency of that part of the plate spring between the front contacts and the point of attachment of the armature. That is, the plate spring is slightly bowed inward 70 toward the core and short leg. Consequently there is a relatively heavy pressure of the front contacts against each other as well as a slight wiping or rubbing action of the co-acting contacts, and, when the magnet winding is deenergized, a quick return of the plate spring to normal because of the strong resiliency previously developed in the plate spring by bending it after the initial engagement of its front contacts. The slit in the 75 end of the plate spring, allows the tongues 7^a, 7^b, thus formed to yield independently of each other, thus insuring a good contact between each set of front contacts. The set of the plate spring is such that in its normal position it will press its back contact point firmly against the back contact point carried by the back contact post. In practice it is not always necessary to make the back contact post adjustable. The front contact 80 posts, however, are made adjustable as hereinbefore described, in order to adjust the spark gap between the front contacts. Owing to the good electrical contact between the plate spring and the long end of the U-frame, 85 the frame may be provided with a terminal post, as indicated at 38 which is intended for the attachment of a conductor leading to ground or to a metallic return, as will be clear from the description hereinafter. 90

In the diagrammatic view, Fig. 1, the two writing lines of the receiver are indicated at Rr and Lr respectively the right writing line Rr extending from the terminal post Rp to a junction J10 with the negative return Xn 95 of the power line, which is grounded at Gr. In the writing line is included the winding Cr of the right bucket coil. Also a resistance Or may be included in this line. The left writing line Lr extends from the terminal post Lp to a junction J11 with the negative return. In this left writing line at the receiver there is included the resistance Ol and the left bucket coil Cl, as usual. In addition, the winding, Cs, of a left writing line 100 relay is also included in the said left writing line. This relay controls one pair of contact points which close and open a branch of the power circuit, which branch contains, in multiple, the winding, Ct, of a paper shifter magnet and the winding Fer of a field control relay, such for example as the relay hereinbefore described. The multiple branches of the power circuit which contain 105 the said windings Ct and Fer are indicated at Xr1 and Xr2 respectively, these being merged in the common branch Xra which includes the contacts controlled by the armature of the left line relay. The branch Xra 110

115

120

125

130

of the power circuit is connected to the negative return at the junction J12.

The parallel branches X_{r1} and X_{r2} are connected to the positive power line, indicated at X_p , and to this there is connected also another branch X_{r3} of the power circuit which terminates at one of the front contacts of the field control relay, for example the contact 14. In the branch X_{r3} are included the usual energizing windings F_{m1} and F_{m2} of the field magnets. Also on each spool of the field magnet there is wound a comparatively small number of turns of resistance wire having a high resistance, for example 400 ohms, these resistance windings being indicated at Om_1 and Om_2 , respectively. These windings are in multiple with the usual magnet windings F_{m1} , F_{m2} , respectively, and are wound in the same direction. These resistance windings serve to absorb to a large extent the field magnet discharge which occurs where the circuit through X_{r3} is broken.

The field control relay has the fixed end 25 of its armature grounded by a conductor X_{rb} connected to the negative return X_n at the junction J13. An alternating current shunt indicated at X_{rc} and joined to the negative return at junction J15 serves 30 to shunt the oscillatory discharge from the field magnet windings around the contact points 14, 16, of the relay, the shunt X_{rc} including a condenser as indicated at 40.

The pen lifter line of the receiver, marked 35 Pr_1 , is divided into two branches, one of which contains the windings P_m of the pen lifter magnet and ends at one of the front contacts of the field control relay, for example, contact 15, while the other branch 40 contains the winding S_x of the signal buzzer and ends at the back contact 19 of the field control relay.

In the diagrammatic illustration Fig. 1 no means is indicated for causing a trembling of the receiver bucket coils. This may be done in any of the old and well known ways as, for example, by employing a slight pulsating current on each writing line or by providing the usual trembler buzzer in shunt 45 with the field magnet windings. As the means for accomplishing this action forms no part of the present invention it need not be described herein, but it is to be understood that some means for accomplishing such vibration or trembling of the receiver 50 bucket coils is to be employed.

The operation of the receiver system is as follows: When the transmitter is put in 55 operation to send variable strength direct currents over the two writing lines, the initial action of such a line current in the left writing line is to energize the left line relay winding C_s , whereupon the said relay attracts its armature and closes the contacts of the power branch X_{ra} , so that current

will flow from the positive power line X_p over the parallel branches X_{r1} and X_{r2} to the junction J12 and thence over the negative power line X_n . When the circuit is closed through the parallel branches X_{r1} 70 and X_{r2} the windings C_t of the paper shifter and the windings F_{cr} of the field control relay are energized. The paper shifter operates in the usual way. The field control relay when its windings are energized 75 attracts its armature and thereby closes its two sets of front contacts, while opening its set of back contacts. One set of front contacts closes that branch of the power circuit which includes the field magnet windings, 80 thereby energizing them, the current flowing from the positive power line X_p over branch X_{r3} , through the field magnet windings F_{m1} , F_{m2} , Om_1 , Om_2 , to the pair of front contacts, thence over the branch X_{rb} 85 to the junction at J13 and back through the negative power line X_n .

Simultaneously with the closing of the field magnet branch by one pair of front contact points, the other pair of front contact points closes, at the receiver, that branch of the pen lifter line which includes the windings P_m of the pen lifter magnet. This puts the receiver in condition so that the pen lifter may be controlled from the transmitter in the usual manner. In this condition that branch of the pen lifter line which contains the signal buzzer windings S_x is open at the back contacts of the field 90 control relay.

When the writing line relay is deenergized by cutting off the current at the transmitter, the power branch X_{ra} is opened by the return of the line relay armature to normal. Thereupon the field control relay 105 is deenergized and its armature returns to normal. This closes the back contacts and puts the branch containing the signal buzzer in condition to receive any signal currents which may be sent out from the transmitter. When the field control relay closes its back contacts it opens the two pair of front contacts, thus opening the circuit through the field magnet windings and the circuit through pen lifter magnet windings. 110 At the opening of the circuit through the field magnet windings, any oscillatory discharge from said field magnet windings will be shunted from the corresponding contacts of the field control relay through the branch 115 X_{rc} .

It is highly important to absorb the discharge from the windings of the paper shifter magnet and the field control relay at the time of breaking the power circuit 120 through X_{ra} due to the opening of the contacts of the writing line relay.

In order to accomplish this result in an effective yet simple manner the windings C_t of the paper shifter magnet and the wind- 125

ings Fcr of the field control relay are shunted by a common shunt branch $Xr4$ containing a condenser 41. In this way the discharge from the field control relay windings 5 cannot affect the paper shifter but will be short circuited by the shunt branch. Also, the discharge from the paper shifter windings will be short circuited by said shunt branch and cannot affect the field control 10 relay. Much trouble in telautograph receivers has been due to the unreliability of the writing line relay. It will be remembered that in a telautograph apparatus of the variable direct current type the writing 15 current for the left writing is relatively weak when the transmitter stylus is close to the unison position, because at this time the maximum resistance of the left rheostat is included in the left writing line circuit. On 20 the other hand when the minimum resistance of the rheostat is in the left writing line circuit, the writing current is greatly increased. The range of variation of the writing line current causes difficulties in operation of 25 the left writing line relays hereinbefore known. The relay should be so sensitive that that it will operate immediately with the minimum current which exists on starting the apparatus and this requires that the 30 moving parts be light and that friction be practically eliminated. On the other hand the relatively heavy currents which occur during transmission produce a residual magnetism in the magnetic circuit of the relay, 35 which tends to hold the relay closed even after the writing line current has ceased. This prevents the proper operation of the paper shifter which is controlled by the writing line relay. Therefore to insure the 40 proper operation of the system, the present invention includes a special type of line relay. In this line relay the armature is arranged to drop away from the magnet core under the action of gravity, the initial start 45 away from the core being assisted by a spring action and the magnet being slightly assisted by spring action at the start in drawing up the armature.

A relay embodying these features is illustrated in Figs. 5 and 6. The frame of the relay is U-shaped and made of soft iron, both legs 50 and 51 being of substantially equal length. The yoke 52 of the frame supports the magnet core 53 and the coil 54. 55 To the outer face of the leg 51 there is fixed a bearing plate 55 of non-magnetic material having a pair of posts 56, projecting downward. The armature 57 consists of a rectangle of soft iron of such length as to extend over the end of the core 53; over the end of the leg 51 and between the posts 56 of the bearing plate 55. That portion of the armature which is between the posts is provided on its lower face with a fine groove or 60 notch extending entirely across the arma-

ture and arranged to receive a fine stiff wire rod 58 which passes through holes in the posts 56 and serves, in connection with the groove or notch, as a bearing for the armature at its outer end, while at the same time 70 allowing a slight play of the armature on the rod 58. The armature is provided on its upper side, which is next to the core, with a spacer or stop device of non-magnetic material, which serves to prevent an actual contact between the armature and the end of the magnet core. In the present example this spacer or stop device indicated at 59 is the projecting end of a rivet hereinafter referred to. 75

To the lower face of the armature there is secured a plate spring 60 which has one end projecting beyond the free end of the armature so as to extend over the end of the leg 50 and over the flanged end of a contact post 61. The plate spring is secured to the armature by two rivets, one of which is located over the end of the magnet core and has its riveted end large enough to serve as the stop device or spacer 59 hereinbefore referred to. The inner end of the plate spring 60 is formed so as to extend away from the armature at an incline and to it there is soldered one end of a coiled flexible conductor 62 whose other end is secured to 90 the bearing plate 55 thus insuring a good electrical connection between the frame of the relay and the plate spring. To the upper surface of the plate spring at its outer, free end is secured a contact point, indicated at 63, arranged to coact with a contact point 64 carried by the outwardly flanged lower end of the contact post 61 which is supported by but insulated from the leg of the U-frame. 95

While the contact post 61 may be connected to the leg 50 in any suitable way, it is most advantageously attached by two screws 65 threaded into the leg 50, the contact post being provided with holes larger 100 than the screws, so as to receive bushing washers 66 of insulating material. Between the contact post and the leg are placed insulating washers 67. Between the bushing washers 66 and the head of the screws 115 65 are placed metal washers 68 and spring locking washers 69. The contact post 61 is not adjustable lengthwise but is accurately constructed to bring its contact point 64 to the correct position, and is made rigid 120 enough to hold this position permanently.

To limit the movement downward of the armature and its plate spring, a hook-like stop device 70 is provided, this being held to the leg 50 by a screw 71. In the best embodiment of the invention the inner face of the hook portion of the stop device is provided with a contact point 72 which coacts with a contact point 73 fixed to the plate 125 spring 60. By means of these two contacts 130

there is less static friction when the armature is pulled up. These contacts act mechanically only and have no electrical function.

It will be noted that the magnetic circuit 5 through the leg 50 includes a relatively great air space between the free end of the armature 57 and the lower end of the leg 50. As a result, the reluctance over this branch of the magnetic circuit is so large that such 10 branch may be considered as not part of the magnetic circuit of the relay, the leg 50 serving practically wholly as a mere support for the contact post 61 and stop device 70. Therefore it may be assumed that the 15 actual operative magnetic circuit of the relay is through the core, the leg 51 of the U-frame, the armature 57, the air-space between the core face and armature and the air-space between the end face of the leg 51 20 and the armature. The latter air-space is very small. The other air-space between the core and the armature is such that the contact point 63 carried by the plate spring 60 will contact with the contact point 64 on the 25 contact post 61 before the stop 59 on the armature has encountered the end of the core. Hence, after the said contact points have closed, the armature is strongly attracted by the core and is pulled up until 30 its stop 59 rests against the core face. This final movement of the armature is possible because the plate spring, whose outer end is stopped by the engagement of the contact 35 points, flexes into an arc-shape, thereby developing the resiliency of the plate spring. Hence, when the magnetic circuit is de-energized the armature is suddenly pulled down from the magnet core, not only by gravity but also by the reaction of the plate 40 spring. This gives a quick break of the electric circuit through the contact points. The armature drops until the plate spring is stopped by the stop-device 70, in which condition the weight of the armature and plate 45 spring is supported by the fulcrum pin or rod 58 at one end and by the hook of the stop-device 70 near the other end. The weight carried by the latter is relatively slight, yet of course causes a slight tension 50 in the plate spring, so that in the open position of the relay, a part of the weight of the armature and plate spring has developed a slight spring reaction in the plate spring, thereby in effect reducing the weight of the 55 armature to be started upward when the magnetic circuit is energized. Hence, by properly proportioning the parts, the armature will respond quickly to the pull of the magnet core and is free to move upward 60 until the contact point 63 on the plate spring touches the contact point 64 on the post, after which the momentum of the armature carries it upward until its stop 59 strikes the face of the core, a part of the momentum being stored by bending the plate spring 65

as before described. By the construction described there is provided a line relay which will respond quickly to the minimum writing line current and yet which will act quickly to open the contacts even if some 70 residual magnetism has been developed by a relatively strong writing line current. With this relay the circuit for the paper shifted mechanism is controlled reliably in accordance with the making and breaking 75 of the writing line circuit at the transmitter.

What I claim is:

1. In a telautograph receiver apparatus, the combination, with bucket coils and writing lines, each writing line having a bucket 80 coil therein, of a writing line relay provided with two contacts and having its windings included in one of said writing lines, a power line arranged to be controlled by the said contacts of the writing line relay and having two parallel branches, a paper shifter mechanism having a magnet winding included in one of said parallel branches, a field control relay having its windings included in the other of said two parallel 85 branches, a field magnet branch from the power line arranged to be controlled by the field control relay, and a field magnet having its windings in said field magnet branch, the bucket coils of the writing lines 90 being located in the field of the said field magnet.

2. In a telautograph receiver apparatus, the combination, with bucket coils and writing lines, each writing line having a bucket coil therein, of a writing line relay provided with two contacts and having its windings included in one of said writing lines, a power line arranged to be controlled by the said contacts of the writing line relay and having two parallel branches, a paper shifter mechanism having its winding included in one of said parallel branches, a field control relay having its windings included in the other of said two parallel 100 branches and provided with a set of back contacts and two sets of front contacts, a field magnet branch from the power line arranged to be controlled by one set of front contacts of the field control relay, a field magnet having its windings in said field magnet branch, the bucket coils of the writing lines being located in the field of the said field magnet, a pen lifter line having two branches, one controlled by the set 105 of back contacts of the field control relay and the other by the remaining set of front contacts of said relay, a signal buzzer having its windings in that branch of the pen lifter line which is controlled by the said back contacts, and a pen lifter having its windings in the other branch of the pen lifter line which is controlled by the said front contacts.

3. In a telautograph apparatus a relay, 110

comprising a U-shaped frame having two legs and a yoke portion, one of said legs being longer than the other, a magnet core secured to the yoke, a winding on said core,
5 a pair of front contact posts secured to the short leg and insulated therefrom, each contact post carrying a contact point, an armature arranged to extend over the end face of the short leg and nearly to the side of
10 the long leg, a plate spring having one end secured to the long leg, said plate spring having its other end free and slotted to form two tongues, each arranged to extend over the respective contact posts, and each
15 carrying a contact point arranged to coact with the respective contact points of the front contact posts, said plate spring being provided with a set such that it tends to hold its contact points out of engagement
20 with those of the front contact posts, a back contact post secured to the said short leg and provided with an end extending outside the plate spring and serving as a stop therefore, coacting back contact points located
25 on the back contact post and on the plate spring respectively, means for securing the armature to the plate spring at a point intermediate their ends, to allow bending of the plate spring, said plate spring pressing
30 the back contact points together firmly when the relay is deenergized and being arranged to bring the two pairs of front contacts together before the armature has completed its movement toward the core when the
35 relay is energized, whereby the plate spring is bent as the armature completes said movement, and a non-magnetic stop device arranged to prevent actual contact of the core and armature.
40 4. In a telautograph apparatus a line relay comprising a U-shaped frame having two legs and a yoke, a magnet core secured to the yoke, a winding on said core, a front contact post secured to and insulated from
45 one leg of the frame, a contact point carried by said contact post, a bearing plate secured to the other leg of the frame and provided with posts at one end projecting beyond the leg of the frame, a pin extending
50 through said posts, an armature having a groove near one end to receive said pin, said armature extending from the bearing plate to and over the end of the magnet core and terminating there, a plate spring
55 secured to said armature and extending over the front contact post, a contact point carried by the plate spring and arranged to contact with the contact point on said post, and a stop device secured to that leg of the
60 frame carrying the front contact post and extending below the plate spring to limit the drop of the armature.

In testimony whereof, I have hereunto
set my hand.

65 ARLEIGH N. VAN NOSTRAND.
